(57) CLAIM

The ornamental design for a cat box cover, as shown and described.

DESCRIPTION

FIG. 1 is a perspective view of a cat box cover showing my new design in use;

FIG. 2 is a front elevation thereof;

FIG. 3 is a right side elevation thereof, the left side elevation being a mirror image thereof;

FIG. 4 is a rear elevation thereof;

FIG. 5 is a top view thereof; and,

FIG. 6 is a bottom view thereof.

The runner with tassels and the scarf shown in broken lines form no part of the claimed design.
